FLUID COMPRESSING ENGINE

Wendell E. Renick, Jackson Township, Pickaway
County, Ohio

Application July 20, 1939, Serial No. 285,505

5 Claims. (Cl. 230—56)

This invention relates to mechanism for compressing and storing in compressed condition fluids especially air or other gases for use in moving materials or operating devices or bodies requiring power.

An object of the invention is to provide an improved and automatic or self regulating mechanism of simple construction in which a motor and pump or compressor are combined and whereby the force and energy of internal combustion is converted into power for subsequent utilization, as for example, operating pressure for tools, mechanism, or materials.

A further object of the invention is to provide improved means for starting the operation of the mechanism and controlling the degree of pressure created.

Other objects of the invention will appear from the disclosure herein.

In the accompanying drawings illustrating an embodiment of the invention.

Figure 1 is a view in side-elevation of the machine with a small portion of one of the fuel supplying pipes slightly cut off.

Fig. 2 is an elevation looking at the right hand end of Fig. 1.

Fig. 3 is principally a vertical longitudinal section on the line III—III Fig. 2.

Fig. 4 is a detail view partly in section on the line IV—IV Fig. 5 and partly in full, illustrating the automatically regulated rotary motor mechanism for starting and maintaining the minimum of desired pressure for the storage.

Fig. 5 is a section on the horizontal line V Fig. 4 illustrating the rotary motor mechanism and some of its ducts and the socket of the motor locking pin or bolt.

Fig. 6 is a transverse section of the rotary 40 starter and distributing valve on the horizontal line VI Fig. 4 with parts omitted.

Fig. 7 is a diagrammatic view with parts in section to better illustrate the scheme of piping.

In the views 10 designates the main shell which 45 includes a cooling water jacket within which shell are formed a middle cylinder 11 and at each of the opposite ends thereof two identical smaller staged cylinders 12 and 13 and 12^a and 13^a respectively all said cylinders being coaxial. Suitably fitted and reciprocable in said cylinders, as one floating structure, are respectively the middle piston 14 and the staged pistons 15 and 16 and 15^a and 16^a, fitted closely with packing rings as indicated on the cylinders. The compressing 50 surfaces of the pistons 15 and 16 and 15^a and 55

16^a are best as shown of equal area to secure uniformity of action in both directions of the reciprocation of the piston structure.

The character 17 designates a pressure storage tank or reservoir which is communicatingly connected by means of pipes 18 with the middle cylinder near its ends, said pipes containing spring actuated valves 19 that open toward the storage tank to permit air compressed by the reciprocations of the middle piston 14 to feed 10 into said storage tank. In the opposite wall of the middle cylinder are spring actuated valves 20 that open inward to permit the sucking of air into the middle cylinder at one side of the middle piston while the said piston is compressing 15 air at the opposite side thereof and forcing it into the storage tank.

21 designates an air carburetor of ordinary construction having a movable butterfly valve or other suitable means provided with an external manually operated control means 22 with a pointer in connection with a scale to regulate and cut off the supply of fuel mixed with air to its compressing cylinders 12 and 12^a. The mixture of fuel and air is to be preliminarily compressed and for this purpose pipes 23 and 23^a alternately conduct the fuel mixture from the carburetor to the ends of the cylinders 12 and 12^a said pipes being provided with spring actuated 20 inwardly opening valves 24 and 24^a so that the piston stages 15 and 15^a alternately suck in the fuel mixture at one stroke while compressing the fuel mixture sucked in at the next preceding stroke. The fuel mixture while thus being compressed in the cylinders 12 and 12^a is alternately fed through pipes 25 and 25^a containing outwardly opening check valves 12^b and 12^c where they are connected with cylinders said pipes alternately discharging the compressed mixture 30 into cylinders 13 and 13^a. The cylinders 13 and 13^a have outwardly closing check valves 13^b and 13^c. The fuel mixture is heavily compressed in the said cylinders 13 and 13^a and is fired and exploded by the heat generated by such compression and constitutes the force for driving the floating piston structure back and forth.

Each of said cylinders 13 and 13^a has an exhaust passage as shown at 30 and 30^a respectively that is covered by the piston therein upon the compression and firing stroke thereof. From the construction shown and described it will be obvious that if the explosive fuel mixture be alternately and regularly fed to the cylinders 13 and 13^a the floating piston structure will be shot 50 55

back and forth with the air compressing or pumping effect in the cylinder 11. The storage tank is shown in Fig. 1 as provided with a cock 17* for utilizing the pressure developed.

5 The means for starting the operation of the mechanism and maintaining the desired pressure in the storage tank includes a suitable housing *a* affixed to the shell 10 of the engine said housing being provided with ducts *b* and *b'* (see 10 Figs. 4 and 6) communicating with the middle cylinder 11 at opposite sides of the zone of travel of the middle piston 14 therein. The said housing *a* is provided with an air or fluid pressure motor composed of two interengaging gear wheels 15 *c* and *c'* of equal diameter and tooth number, the latter, *c'*, having coaxially and suitably connected with its inner face for rotation therewith a tapered plug or valve *d*. The said valve *d* is provided with annular grooves or ducts *e* and *f*, and 20 between said annular ducts with six longitudinal ducts, three of which, designated *g* communicate only with the annular duct *e*, while the other three of which, *h*, communicate only with the annular duct or groove *f*. The said longitudinal ducts *g* and *h* are alternately and equally spaced 25 annularly 60 degrees apart on the valve. The annular duct or groove *e* communicates with an intake pressure port *i* in the housing said port taking pressure from the storage tank 17, and the 30 annular duct or groove *f* communicates with an exhaust port *j* in the housing to the atmosphere.

Installed or formed in the housing *a* is a cylindrical chamber (made up of several sections) having a closed outer end and containing suitable transverse partitions *l* and *m* and two spring diaphragms *n* and *o* carrying affixed thereto the motor locking pin *x* to engage socket *x'* in the motor wheel *c*. The diaphragms *n* and *o* respond to pressures as hereinafter set forth. The middle chamber *k* is connected by a duct *q* with the pressure supply port *i*, and the two end chambers *r* and *s* are connected by ducts *t* and *u* the latter functioning with a duct or passage *v* shown in broken lines Fig. 4 in the side of a tooth of the fluid motor wheel *c* so that when said groove *v* coincides with ducts *u* and *c'* there is formed a discharging passage from the pressure tank. Pressure to operate the motor is controlled by the spring actuated valve *w* secured to the motor locking pin *x* and having therebelow a spring *x'* resting on a screw threaded plug *y* said plug being adjustable by means of a hand wheel *z* to vary the resistance of spring *x'*. The partition 55 *l* has an opening formed with a valve seat for the valve *w* and said opening can be closed either by the hand wheel or by pressure in chamber *k*. The chamber *s* has a slow pin leak at *s'* to exhaust residual pressure in said chamber *s*. 60 In operation of the engine the pressure ducts of the starter are constantly subject to pressure in the storage tank through the port *i* and the valve channel *e*. The exhaust ducts *h* have constant communication with the atmosphere 65 through the valve channel *f* and outlet *j*. The passages at *b*, *b'* in the housing take pressure from the storage tank.

70 It is desirable that the pressure generated by the engine shall by its own action result in a substantially uniform predetermined pressure in the storage tank. To accomplish this the described means in the housing *a* is constructed to serve as a "pop open valve," said means including the pressure diaphragm *n*, the gear motor lock pin *x*, 75 the hand actuated screw *z*, the valve *w*, and

spring *x'* therebelow the resilience of which last is regulated by said actuated hand screw. The pressure duct *q* and cylinder *k* permit pressure from the storage tank duct *i* to thrust against diaphragm *n* which is opposed by spring *n'*. The 5 force of the spring *n'* against diaphragm *n* is adjusted by compensating spring *x'* with hand wheel *z*. Therefore it will be noted that when pressure in cylinder *k* fails to overpower spring *n'* that spring will thrust diaphragm *n* outward 10 causing the lock pin *x* to open valve *w* and remove the gear motor lock pin *x* from its seat. When the seat of valve *w* is thus opened the passage *t* conducts pressure to the rotary gear motor at intake *c'* causing the gears of the motor to 15 rotate in opposite directions as indicated by arrows the pressure exhausting through port *c*. The passage channel *v* is properly located or timed in relation to the valve *d* so that one revolution of the passage channel *v* permits diversion of pressure in channel *t* and passage *u* to cylinder *s* through passage *u* to cause the diaphragm *o* supplemented by pressure on diaphragm *n* to thrust inward the lock pin *x* and close valve *w*. At this point it will be noted that the relationship of the motor gears and the valve *d* is such that when the motor pin lock seat *x'* is at a point just after the passage of the channel *v* and has left passage *u* the lock pin is thrust into said seat *x'* by reason of the inward pressure on diaphragms *o* and *n*. The storage pressure in its tank is thus cut off from the motor by reason of the closing of valve *w*. The storage pressure can therefore be varied and regulated by changing the pressure of spring *x'* by adjusting hand wheel *z*. Fig. 6 shows the valve's locked position.

When the pressure in the tank drops to less than permitted by the tension of spring *n'* diaphragm *n* is pushed outward by the action of spring *n'* thereby releasing lock pin *x* from its seat *x'* and thus automatically causing the starting of the motor with the pressure passing through valve seat *w* into passage *t*. The means for starting the engine need not contain the means for automatic control but can consist of the housing with a hand operated valve like that designated *d*.

The operation of the engine can be stopped at 50 any time by cutting off the fuel.

By obvious change of the inlet and outlet valves of the cylinder 11 the middle piston 14 can operate to vacuumize tank 17 or other vessel connected therewith.

55 The employment in any engine of a mixture of a volatilizable fuel with air and igniting initially the mixture by the heat of compression alone is believed to be novel. This concept differs from the Diesel invention, as I understand it, in that the latter compresses the air alone to an igniting temperature and then through external devices injects the fuel in the raw form into the compressed air. In my invention the explosive mixture of fuel and air are in the form of a gas 60 or vapor at the time of the compression. In my invention I do not time the explosion but time the supply of the explosive mixture. Any vaporizable combustible can be used such as commonly known as ordinary furnace oil or fuel oil.

70 Counting the two sides of the middle piston as distinct pistons the opposite sides of the combined pistons can be termed as three stages.

75 Generally the forms, number, proportions and locations of the parts can be changed within the

skill and judgment of the engineer without departing from the gist of the invention as claimed.

What I claim is:

- 5 1. In a fluid compressing engine of the kind described having a storage tank for the compressed fluid, a starter means communicatingly connected with the pressure of said tank, said starter means including a housing having a rotary fluid pressure motor actuated by the pressure of the tank and a distributing valve actuatable by said motor, and means in said housing actuated by an excess of a predetermined pressure in said tank for releasing such excess of pressure and arresting the operation of said motor.
- 10 2. A fluid compressing engine including a substantially integral piston structure composed of a middle fluid pumping piston having extended symmetrically from each of the opposite faces thereof substantially identical two staged pistons of smaller diameters than that of the said middle piston, a suitably staged cylinder structure for receiving and inclosing the several parts of said piston structure and permitting axial reciprocation of the latter as a unit therein, said cylinder structure provided with suitable ports and valves therefor, and conducting means whereby fuel is supplied alternately to the first of said staged cylinders, and conducting means whereby the second of said staged cylinders are alternately charged with said fuel for firing compression.
- 15 3. A fluid compressing engine including a substantially integral piston structure composed of a middle fluid pumping piston having extended symmetrically from each of the opposite faces thereof substantially identical two staged pistons of smaller diameters than that of the said middle piston, a suitably staged cylinder structure for receiving and inclosing the several parts of said piston structure and permitting axial reciprocation of the latter as a unit therein, said cylinder structure provided with suitable ports and valves therefor and conducting means whereby fuel is supplied alternately to the first of said staged cylinders, and conducting means whereby the second of said staged cylinders are alternately charged with said fuel for firing compression.
- 20 4. A fluid compressing engine including a substantially integral piston structure composed of a middle fluid pumping piston having extended symmetrically from each of the opposite faces thereof substantially identical two staged pistons of less diameter than that of the said middle piston, a suitably staged cylinder structure for receiving and inclosing the several parts of said piston structure and permitting axial reciprocation of the latter as a unit therein, said cylinder structure provided with suitable ports and valves therefor, and conducting means whereby fuel is supplied alternately to the first of said staged cylinders, and conducting means whereby the second of said staged cylinders are alternately charged with said fuel for firing compression, a fluid pressure reservoir, starter means for the compressing engine including a housing having fluid pressure motor actuated by the pressure of the said reservoir and a distributing valve actuatable by the said motor and means in said housing actuated by an excess of predetermined pressure in said tank for releasing such excess pressure.
- 25 5. In an engine of the kind described, a piston structure including a single middle portion having projecting from each face thereof two staged pistons of smaller diameter than that of the middle piston, the respective compressing ends of the pistons at one side of said middle piston being substantially equal to those at the other, a suitable cylinder structure for said pistons and in which said piston structure is reciprocable as a unit, means for feeding a combustible fuel to the cylinder of the first of said staged pistons, and means for alternately conducting said compressed fuel for combustion to the second of the said staged pistons.

WENDELL E. RENICK. 45
